UNITED STATES PATENT OFFICE.

JOSEPH RUSSEL, OF ST. LOUIS, MISSOURI.

SHOE-CLEANER.

1,225,502.

Specification of Letters Patent.

Patented May 8, 1917.

Application filed May 3, 1912. Serial No. 895,003.

To all whom it may concern:

Be it known that I, JOSEPH RUSSEL, a citizen of the United States, residing at St. Louis, in the State of Missouri, have invented certain new and useful Improvements in Shoe-Cleaners, of which the following is a specification, reference being had therein to the accompanying drawing.

This invention relates to an improvement in shoe brushes, and one of the objects of the present invention is the provision of a simple and efficient device which carries means for applying a polishing material to the shoe and also means for brushing and polishing the shoe.

A further object of the invention is the provision of an improved device of this character provided with means for carrying a supply of polishing material and with means for controlling the discharge of said polishing material so that it may be properly distributed onto the shoe to be cleaned.

A further object of the invention is the provision of a device of this character in which means are provided for carrying both a paste and a liquid and for independently controlling the discharge of such materials so that they may be readily applied to the shoe to be cleaned.

Other objects of the invention will be apparent from the detailed description hereinafter when read in connection with the accompanying drawings forming a part hereof, wherein a convenient embodiment of the invention is illustrated, and wherein like characters of reference refer to similar parts in the several views.

In the drawings:

Figure 1 is a side elevation of the improved shoe cleaner;

Fig. 2 is a longitudinal section;

Figs. 3 and 4 are transverse sectional views.

Fig. 5 is a detail sectional view of the construction employed for holding the polishing member locked against rotation in the arms which support the same.

Figs. 6 and 7 are detail sectional views of the valve construction.

Referring now more particularly to the drawings, A designates an elongated paste receptacle, which, in the embodiment of the invention illustrated in the drawings is rectangular in cross section. The paste receptacle A is open at its inner end and the outer end thereof is provided with a down-

wardly turned nozzle or outlet a which is provided with a restricted discharge. Secured to the paste receptacle A and extending along the inside thereof is an elongated tubular liquid container B, the outer end of which is provided with a downwardly turned nozzle or outlet portion b which is adapted to lie directly alongside of the downwardly turned portion a of the paste receptacle A. C designates a dauber which comprises a body portion c from which project the usual bristles or brushes. The dauber C is secured in any suitable manner against the underside of the paste receptacle A, a suitable opening c' being provided in the base c thereof through which project the downwardly turned portions a and b of the paste receptacle A and the liquid container B. The outer surface of the body c of the dauber C is also conveniently provided with a groove c' therein which is adapted to receive the tubular liquid container B, thus enabling the dauber to be secured against the underside of the paste receptacle A. In practice a quantity of paste is placed within the receptacle A and any suitable means may be employed for forcing some of the paste in said receptacle out through the nozzle portion a thereof so that it may be distributed onto the shoe by the dauber C, and while I have illustrated in the drawings, one construction which may be used to effect the discharge of the paste from the receptacle A, it will be understood that the invention is not to be limited to the particular form and construction shown. In the construction illustrated, D designates a shaft, one end of which is loosely mounted in a socket or bearing d provided in the outer end of the paste tube or receptacle A and the other end of which projects beyond the open inner end of said paste receptacle and terminates in a portion d' fashioned to permit rotation of the shaft D. Loosely mounted on the shaft D is a handle d' for manipulating the cleaner. Loosely mounted upon the shaft D adjacent the inner end of the handle d' and rigidly connected thereto is a cap d'' for closing the inner end of the paste receptacle A. The cap d'' is held in any suitable manner against longitudinal movement on the shaft D but said shaft is free to turn in said cap. Any suitable means is provided for locking the cap d'' onto the open end of the paste receptacle A. In the embodiment of the invention illustrated the cap d'' and the adj-

cent portion of the paste receptacle A are provided one with a socket and the other with a projection, the elasticity of the metal forming the parts permitting the projection to snap into the socket as the cap is moved to position onto the open end of the paste receptacle. The portion of the shaft D which lies within the paste receptacle A is threaded, and threaded upon said threaded portion of the shaft is a follower plate D' which is rectangular in shape to correspond to the cross section of the paste receptacle A. From this construction it will be seen that as the shaft D is rotated, the follower plate D' will be caused to travel in the paste receptacle A and will in consequence of such movement, force a portion of the contents of said receptacle out through the nozzle a thereof, so that it can be readily distributed onto the shoe by means of the dauber C. The container B is provided with a suitable filling opening B⁵ and removable closure B⁴, and suitable means may be utilized for forcing a portion of the liquid contents of the container B out through the nozzle b thereof. In the embodiment of the invention illustrated, I have shown the container B as provided with a valve B' from which extends a valve rod B² which projects outwardly beyond the inner end of the liquid holder B and terminates in an operating knob or handle b' which is adapted to lie alongside of the handle d' heretofore referred to. A spring b² serves to normally hold the valve B' pressed rearwardly against a valve seat B³ formed in the liquid container adjacent the outer end thereof, thus preventing the passage of any of the liquid contained in the container B through the outlet b thereof. In this position of the valve the operating knob b' occupies its rearmost position. Whenever it is desired to discharge any of the liquid contents of the container B through the nozzle b thereof, the operator merely presses on the knob or handle b'. As soon as the pressure on the knob or handle b' is released, the spring b² will return the same to its normal closed position, said valve, as clearly shown in Fig. 4 of the drawing, being spaced from the walls of the container B.

Projecting upwardly from the end portions of the paste receptacle A are arms E E. Journaled in the upper portions of the arms E E is a polishing member, said member comprising a body portion F, one side of which is faced with a covering F' of felt or other suitable material and the other side of which is provided with a plurality of bristles forming a brush F². Means is provided for shifting the member F to bring either the felt face F' or the brush face F² thereof uppermost. In the embodiment of the invention illustrated, the arms E E are formed of spring metal, and the ad-

jacent portions of said arms and the body F of the polishing member are provided with suitable projections f' and recesses f² which when in engagement, serve to hold the polishing member locked against rotation in the arms E E with either face thereof uppermost. 70

The nozzles or discharge mouths of the paste or liquid receptacles may be provided with a screen such as represented at G which will serve to prevent entrance of dust into the receptacles and also act to prevent escape of the liquid or paste and retard the discharge of the same save when subjected to force when it is intended to feed the 80 polishing preparation from the implement. 75

The paste being inserted into the paste receptacle of course will remain there for a considerable period of time and may perhaps become somewhat stiff or hardened, 85 and to secure a proper breaking up of the same I provide the follower D' with projecting pins H adapted to engage one end of the paste body or cartridge adapted to co-operate in conjunction with a rotary cutter 90 or shaving device I at the discharge end of the follower shaft, the latter being fixed to the shaft and adapted to rotate therewith to cut or break up the paste so that it can freely discharge under the pressure of the follower 95 through the discharge nozzle. 5

I believe the operation of the device will be apparent from the above description, and it will be obvious, that as distinguished from the ordinary method of polishing shoes, involving the objectionable use of the hands in applying paste, etc., I have provided an implement capable of performing its expected uses in a clean and satisfactory manner, the polishing preparation being entirely 105 confined and emitted directly on the shoe, thus obviating any liability to soil the hands of the user or to soil the implement itself. 100

While a convenient embodiment of the invention is illustrated in the accompanying 110 drawings, it will be understood that many changes may be made in the form and construction shown without departing from the spirit and scope of the invention as defined in the appended claims. 115

I claim:

1. In a device of the character described, a polish distributing member, a paste receptacle and a liquid polish container provided with outlets terminating adjacent said polish distributing member, and independent means for controlling the discharge of material from said containers through the outlets thereof. 120

2. In a device of the character described, a paste receptacle provided with a downwardly turned outlet portion, a liquid container secured alongside of said paste receptacle and provided with a downwardly turned outlet portion, a polish distributing 125

130

member apertured to receive the downwardly turned portions of the paste receptacle and liquid container, a handle for the device, and independent means for controlling the discharge of material from the paste receptacle and liquid container.

3. In a device of the character described, a paste receptacle provided with a downwardly turned outlet portion, a liquid container extending along the underside of said paste receptacle and provided with a downwardly turned outlet portion lying alongside the downwardly turned outlet portion of the paste receptacle, a polish distributing member apertured to receive the downwardly turned portions of the paste and liquid containers, a handle for the device, and independent means for controlling the discharge of material from the paste receptacle and liquid container.

4. In a device of the character described, a paste receptacle provided with a discharge outlet, a liquid container secured to said paste receptacle and provided with a discharge outlet, a shaft rotatably supported in said paste receptacle and projecting without the same, a handle secured to the projecting portion of said shaft, means acting upon the rotation of said shaft for feeding material from the paste receptacle through the outlet thereof, and means positioned adjacent said handle for controlling the discharge of liquid from the liquid container.

5. In a device of the character described, a polish receptacle provided with an outlet, a polish distributing member at said outlet, in combination with means for forcing the discharge of the polish from the polish receptacle, and means associated with said last mentioned means for cutting or breaking up a polishing paste within the receptacle.

6. In a device of the character described, a paste receptacle having an outlet, means for discharging the paste from said receptacle through said outlet, and means in the

receptacle for breaking up the paste in the receptacle when hardened, substantially as described.

7. In a device of the character described, a paste receptacle having an outlet, means for discharging the paste from said receptacle through said outlet, and means in the receptacle for breaking up the paste when hardened, said means including a cutter arranged adjacent to the outlet to operate on the material as it is discharged from the receptacle, substantially as described.

8. In a device of the character described, a paste receptacle having an outlet, means for discharging the paste from said receptacle through said outlet, means in the receptacle for breaking up the paste in the receptacle when hardened, said means including a cutter adjacent to the outlet, and a follower provided with projections co-65 operating with said cutter.

9. In a device of the character described, a paste receptacle provided with an outlet, a shaft rotatably supported in said paste receptacle, means for rotating said shaft, a follower plate arranged within the receptacle to force material therefrom, said follower plate being threaded upon said shaft, and means in the receptacle for breaking up the paste when hardened, said means including a cutter fixed to the shaft for rotation therewith.

10. In a device of the class described, a paste receptacle having an outlet, a follower plate in said receptacle to force material therefrom, a rotary device in the receptacle for breaking up the paste when hardened, and means common to both the follower and said rotary device for operating the same.

In testimony whereof I affix my signature in presence of two witnesses.

JOSEPH RUSSEL.
